UNITED STATES PATENT OFFICE.

HALSEY D. PAYNE, ALVIN W. DE CLERQUE, AND SIDNEY T. SJOBERG, OF CHICAGO, ILLINOIS, ASSIGNEES, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

WASHING MACHINE WITH FOLDING WRINGER.

Application filed December 19, 1921. Serial No. 523,604.

This invention relates to laundry machinery of the type commonly used in homes. The object of the invention is to so equip the cabinet of a power driven washing machine with a wringer for use in wringing the clothes delivered from the cabinet that the wringer may be tilted between its normal working position standing up above the plane of the upper edge of the tub to a position where it is below such plane, and therefore capable of being concealed by any sort of cover which may be placed across the top of the cabinet. Another object is to swing the wringer about a vertical axis so that it may be used in different selected angular positions and to lock it in each of such positions. Still another object is to move the wringer in either of the two described directions without disturbing the application of power to the wringer.

It is well known that it is necessary to cover up wringers and other washing machinery between periods of use, in order to keep such devices from getting dirty and deteriorating by mere contact with ordinary air, and one of the reasons for so mounting the wringer is to enable such a cover to be readily applied.

The invention consists in means for carrying out the foregoing and other objects which can be easily and comparatively cheaply made, which is satisfactory in use and is not readily liable to get out of order. It also consists in other details and features of construction hereafter more fully set forth in the specification and claims.

Referring to the drawings, in which similar numerals represent the same parts throughout the several views—

Figure 1 is a side view partially in section of the mechanism illustrating this invention in its preferred form;

Figure 2 is an end view taken on the line 2—2 of Figure 1;

Figures 3 and 4 are perspective views of the pivot mechanism for the wringer, the parts being separated so as to show the surfaces of contact.

The subject-matter shown and hereafter described and claimed, in so far as it applies to the foregoing figures, is a continuation of our prior application, Serial No. 408,704, filed September 7, 1920, and aban-

doned contemporaneously with the filing of this case. An improved modification of certain features of the foregoing figures is shown in the following additional figures, in which—

Figure 5 is a side elevation, and Figure 6 an end view of mechanism corresponding to Figures 1 and 2, except that the mechanism is moved up in the washing cabinet to a point where the pivotal mechanism for shifting the wringer is above the top of the cabinet, and in that a latch mechanism is provided for locking the wringer in its different angular positions as it swings in a horizontal plane about the vertical power shaft;

Figure 7 shows the same identical parts as original Figures 3 and 4, modified only in that the member 21 is provided with perforations in which the latch referred to in connection with Figures 5 and 6 may enter;

Figure 8 is a perspective view of the bracket mechanism showing the latch mechanism for locking the wringer in a horizontal plane applied thereto; and

Figure 9 shows the latchable pivot structure of Figure 8 positioned as in Figure 1.

The mechanism of this invention, conventionally shown, is applied to the upper portion of a washing cabinet 10 over whose upper edge 12 it is desirable to place some sort of a cover device. Inside of this cabinet secured to one wall by suitable attaching devices as bolts and screws 14 is a bracket 16. Detachably inserted in a vertical perforation 18 in this bracket is a horizontally rotatable hollow case 20 within which is located a horizontally revolving bevel gear 22 rigid on the upper end of a shaft 24 driven by the washing machine proper forming no part of this invention and therefore not shown in detail. The rotatability of case 20 in the bracket 18 arises from the fact that as clearly shown in Figure 4, the case 20 is provided with a downwardly projecting cylindrical stem 21 which rests in the bracket as shown in Figure 1. In the absence of bottom fastenings for stem 21 it can rotate freely inside bracket 18 and about shaft 24, with which it is concentric, as shown in Figure 1. Also enclosed within the case 20 is another bevel gear 26 meshing with gear 22, and carrying a horizontal

shaft 28 on which is mounted a sprocket gear 30 over which passes sprocket chain 32 driving a pinion 34 on the end of the shaft of lower wringer roller 36. This roller is journaled at its opposite ends in the wringer frame member 38—40 of ordinary construction rising from a conventional bracket 42. The lower end of frame member 38 is preferably constructed as shown in Figure 4 with an annular recess 44 adapted to fit over and revolve upon a cylindrical lug 46 formed upon case 20, as shown in Figure 4 with an annular recess 44 adapted to fit over and revolve upon a cylindrical lug 46 formed upon case 20, as shown in detail in Figure 3. The axis of rotation of member 38 on member 46 is concentric to shaft 28 which passes through a perforation 48, clearly appearing in Figure 4, in member 38. The whole wringer mechanism is therefore rotatable through an arc lying in a plane at right angles to the wringer rolls from the full line position of Figures 1 and 2, where the wringer is in operative position for use, to the dotted line position of Figure 2, where it is below the upper edge 12 of the washing cabinet, and therefore out of the way. It is also, when elevated through any reasonable angle desired, rotatable in a horizontal plane about the pivotal connection between casting 20 and bracket 16.

The wringer may be locked in either of these positions by any suitable means. In the particular embodiment of the invention the securing means takes the form of a reciprocatable pin 50 mounted in a suitable lug 52 extending from case 20 and urged by a spring 54 to selectively enter holes 55, 56, 57 and 58 formed in the member 38 to lock the wringer in one or the other of the positions shown, the hole 56 being used when the wringer is upright, as shown in Figure 1, the hole 58 being used when the wringer is lowered to the position of Figure 2.

The pin 50 is retractible against the action of the spring 54 by use of the handle 60 adapted to be operated by the operator when he desires to selectively position the wringer.

It may be noted that owing to the fact that the arm 38 rocks about the axis of shaft 28 the operating relationship of the driving parts of the wringer is undisturbed by the rocking movement of the wringer in moving from its elevated to its depressed position. That is, the wringer rolls can be rotated by power shaft 24 when the wringer is lowered just as well as when it is raised, this not that it is desirable to do so, but to insure the wringer being always ready to operate without danger of its mechanism being out of order because of the lowering operation.

It will be noticed that when the wringer is depressed and the cabinet is closed up by placing a cover over its upper edge, the en-

tire mechanism is capable of very neat appearance, even though it may be kept in a room normally used for other purposes than washing, a condition which could not exist if the wringer had to stand in upright position.

The pivot mechanism for swinging the wringer about the axis of the vertical power shaft 24, shown in Figures 5 to 8, is exactly the same as that shown in Figures 1 to 4, except that the vertical tubular member 70 carried by the bracket is provided with a horizontally reciprocatable pin or bolt 72 of conventional construction, normally urged inward by a spring 74 so that the end of the bolt may enter and lock in selected ones of suitable holes 76 provided for it in the downwardly extending cylindrical stem 21^a corresponding to the stem 21 of Figures 1 and 3. When it is desired to shift the wringer about the axis of shaft 24, the operator simply withdraws the bolt from opening 76 and rotates the wringer until the bolt is in position to enter another corresponding perforation 76 provided in member 21^a, whereupon the wringer is located in a new horizontal position.

That the selective locking mechanism is perfectly applicable to a structure in which the wringer is positioned as shown in Figures 1 to 4 is made clear in Figure 9, in which latch mechanism 72—78 is inserted in the lower part of the exact device of Figure 1.

As explained in the description, Figures 5 to 8 differ in no other respects than those just pointed out from Figures 1 to 4, except that the pivotal center of the wringer about the horizontal shaft 28 is raised to a point above the upper edge of the washing cabinet, this to show that the mechanism is capable of such a positioning, without otherwise departing from the invention should the operator desire to so position the wringer.

What we claim is:

1. In a device of the character described, a cabinet, a wringer, means pivoting the wringer at a point inside the cabinet and below its upper edge in such a manner that the wringer may be swung in an arc in a horizontal plane and in an arc lying in a plane at right angles to the body of the wringer from an elevated position where it places the wringer above the top of the cabinet to a position where the wringer is below the top of the cabinet, means for locking said wringer in its elevated position and power driven means operating through the cabinet adapted to deliver power to the wringer rolls.

2. In a device of the character described, a cabinet, a wringer, means pivoting the wringer at a point inside the cabinet and below its upper edge in such a manner that

the wringer may be swung in an arc in a horizontal plane and in an arc lying in a plane at right angles to the body of the wringer from an elevated position where it places the wringer above the top of the cabinet to a position where the wringer is below the top of the cabinet, means for locking said wringer in its elevated position, means for selectively locking the wringer in its 10 different horizontal positions, and power driven means operating through the cabinet adapted to deliver power to the wringer rolls.

3. In a device as described, a cabinet, a wringer provided with rolls mounted in a frame, means pivoting the frame at a point inside the cabinet and below its upper edge in such a manner that the wringer may swing both in an arc in a horizontal plane 15 and in an arc lying in a plane at right angles to the wringer rolls from an elevated position where it places the rolls above the top of the cabinet to a lower position where the wringer is below the top of the cabinet, 20 means for selectively locking the wringer in each of said positions, and power driven means operating through the cabinet adapted to deliver power to the wringer rolls, said power means being undisturbed as the 25 wringer moves in either of its two arcs of travel.

4. In mechanism of the class described, a washing cabinet, a wringer mounted in a frame, means pivoting the frame at a point 30 inside the cabinet and below its upper edge in such a manner that the wringer may swing from an elevated position where it extends above the top of the cabinet to a lower position where it is below the top of the cabinet, means for selectively locking the wringer in each of said positions and power 35 driven means operating through the cabinet adapted to deliver power to the wringer rolls, said power means being undisturbed 40 as the wringer moves between its said extreme positions.

5. In mechanism of the class described, a washing cabinet, a wringer provided with

rolls mounted in a frame, means pivoting the frame at a point inside the cabinet and 50 below its upper edge in such a manner that the wringer may swing in an arc lying in a plane at right angles to the wringer rolls from an elevated position where it extends above the top of the cabinet to a lower position 55 where it is below the top of the cabinet, means for selectively locking the wringer in each of said positions, and power driven means operating through the cabinet adapted to deliver power to the wringer rolls, 60 said power means being undisturbed as the wringer moves between its said extreme positions.

6. In a washing machine, the combination with a cabinet and a power driven wringer, 65 of a vertical shaft within the cabinet, means for permitting a swinging movement of the wringer about the shaft as an axis above the top of the cabinet, and means fixed relatively to the top of the cabinet for permitting a 70 single movement of the wringer about an axis perpendicular to the shaft to a position below the top of the cabinet.

7. In a washing machine, a cabinet, a drive shaft therein, a wringer driven by the 75 shaft, and means permitting a single folding movement of the wringer from an operating position above the top of the cabinet to a stored position below the top of the cabinet and also a swinging movement of the 80 wringer in its operating position.

8. In a power-wringer construction, the combination with a vertical drive shaft and a wringer disposed in a frame, of means associated with the upper end of the shaft 85 for supporting the wringer in its frame in operative relation with the shaft to permit the frame to swing around the shaft as an axis above a predetermined plane and also to permit it to move with a single folding 90 movement to a position below said plane.

In witness whereof, we have hereunto subscribed our names.
